RAZOR STROP

William C. Davis, Los Angeles, Calif.

Application March 5, 1930. Serial No. 433,391

2 Claims. (Cl. 51—200)

My invention relates to a razor strop.

In making razor strops of leather, the hair side is the one used for stropping. However, it is difficult to secure a perfect edge on a razor when using such a strop for the reason that the structure of the hair side of the leather has a certain inclination somewhat analogous to the pile of a carpet, so that it offers more friction when the razor is stropped in one direction than in the other. It is an object of this invention to provide a leather strop so constructed that it offers an equal amount of friction in either direction. For this purpose I assemble strips of leather turned on edge so that the hair side is disposed between the faces of the strop, and fasten them together by suitable means.

With the above and other objects in view which will appear as the description proceeds, my invention consists in the construction and arrangement of parts hereinafter shown and described. In the accompanying drawing which forms a part of this specification I have illustrated a preferred embodiment of my invention, in which, Fig. 1 is a perspective view of a strop made in accordance with my invention;

Fig. 2 is an enlarged cross section on the line 2—2 of Fig. 1;

Fig. 3 is a similar view on the line 3—3 of Fig. 1;

Fig. 4 is a view similar to Fig. 3, of a strop which is cemented to a canvas backing.

Referring to the drawing, 1 indicates the body of the strop, having conventional holding means 2 and a hand grip 3. The body 1 is composed of a series of strips of leather 4 preferably of the same size as shown in Figs. 2, 3 and 4. The hair side of the strips is indicated at 4', which

as shown in the drawing is disposed between the upper face 1' and the lower face 1² of the strop. The strips 4 may be held together in assembled relation by any suitable means such as cement, though I prefer to sew them together, using a flexible wire 5 preferably of brass which forms stitches as indicated at 6. Along the edges of the strop the wire 5 passes transversely through the strips 4 as clearly shown in Fig. 2.

In the modification shown in Figs. 3 and 4 I cement the face 12 to a suitable canvas back 7.

A strop made in accordance with this invention will present a stropping face 1' or 1² pressing the edges of the strips of leather 4 which offer a uniform resistance of friction to the stropping of the razor in either direction, thus putting a perfect edge on a razor.

Various changes may be made in the principles of the invention by those skilled in the art without departing from the spirit of the invention as claimed.

I claim:

1. A razor strop comprising a plurality of leather strips of uniform size and shape assembled face to face to form smooth upper and lower strop faces with the hair side of the strips disposed between the faces of the strop, and means for holding said strips together.

2. A razor strop comprising a plurality of leather strips of uniform size and shape assembled face to face to form smooth upper and lower strop faces with the hair side of the strips disposed between the faces of the strop, said strips being sewed together with flexible material passing transversely through the strips.

WM. C. DAVIS.
